(57) **CLAIM**

The ornamental design for a pegboard adapter, as shown and described.

DESCRIPTION

FIG. 1 is a perspective view of a first embodiment of a pegboard adapter showing my new design.

FIG. 2 depicts a front view of the pegboard adapter of FIG. 1.

FIG. 3 depicts a rear view of the pegboard adapter in FIG. 1.

FIG. 4 depicts a top view of the pegboard adapter in FIG. 1.

FIG. 5 depicts a bottom view of the pegboard adapter in FIG. 1.

FIG. 6 depicts a left view of the pegboard adapter in FIG. 1. With an exception of the broken line prongs, the right side view being a mirror image thereof.

FIG. 7 is a perspective view of the pegboard adapter in FIG. 1 shown in a first environment of use;

FIG. 8 is a perspective view of the pegboard adapter in FIG. 1 shown in a second environment of use;

FIG. 9 is a perspective view of a second embodiment of a pegboard adapter showing my new design;

FIG. 10 depicts a front view of the pegboard adapter of FIG. 9.

FIG. 11 depicts a rear view of the pegboard adapter in FIG. 9.

FIG. 12 depicts a top view of the pegboard adapter in FIG. 9.

FIG. 13 depicts a bottom view of the pegboard adapter in FIG. 9.

FIG. 14 depicts a left view of the pegboard adapter in FIG. 9. With an exception of the broken line prongs, the right side view being a mirror image thereof.

FIG. 15 is a perspective view of a third embodiment of a pegboard adapter showing my new design;

FIG. 16 depicts a front view of the pegboard adapter of FIG. 15.

FIG. 17 depicts a rear view of the pegboard adapter in FIG. 15.

FIG. 18 depicts a top view of the pegboard adapter in FIG. 15.

FIG. 19 depicts a bottom view of the pegboard adapter in FIG. 15.

FIG. 20 depicts a left view of the pegboard adapter in FIG. 15. With an exception of the broken line prongs, the right side view being a mirror image thereof.

FIG. 21 is a perspective view of a fourth embodiment of a pegboard adapter showing my new design;

FIG. 22 depicts a front view of the pegboard adapter of FIG. 21.

(Continued)

FIG. 23 depicts a rear view of the pegboard adapter in FIG. 21.

FIG. 24 depicts a top view of the pegboard adapter in FIG. 21.

FIG. 25 depicts a bottom view of the pegboard adapter in FIG. 21; and,

FIG. 26 depicts a left view of the pegboard adapter in FIG. 21. With an exception of the broken line prongs, the right side view being a mirror image thereof.

In the drawings, the dash-dash broken lines on the prongs and bottom flange represent portions of the article which form no part of the claimed design. The remaining broken lines in FIGS. 7 and 8 illustrate environmental subject matter which forms no part of the claimed design. The dot-dash broken lines represent a boundary to the claimed design and form no part thereof. The article is shown with a symbolic break in its length and height. The appearance of any portion of the article between the break lines forms no part of the claimed design.
